UNITED STATES PATENT OFFICE.

THOMAS J. REGAN, OF BROCKTON, MASSACHUSETTS, ASSIGNOR OF TWO-THIRDS TO GEO. E. KEITH COMPANY, OF BROCKTON, MASSACHUSETTS, A CORPORATION OF MASSACHUSETTS.

BOOT AND SHOE.

No. 887,846.

Specification of Letters Patent.

Patented May 19, 1908.

Application filed December 19, 1905. Serial No. 292,412.

To all whom it may concern:

Be it known that I, THOMAS J. REGAN, of Brockton, in the county of Plymouth and State of Massachusetts, have invented certain new and useful Improvements in Boots and Shoes, of which the following is a specification.

This invention has for its object to provide a boot or shoe with an instep support located at the inner side of the interior of the shoe at the shank portion thereof and forming a structural part of the shoe, the said supporter being therefore kept in its proper place without liability of displacement.

15 The invention consists in the improvements which I will now proceed to describe and claim.

Of the accompanying drawings, forming a part of this specification:—Figure 1 represents a bottom plan view of the inner sole of a welted shoe embodying my invention. Fig. 2 represents an edge view of the said inner sole. Fig. 3 represents a section on line 3—3 of Fig. 1. Fig. 4 represents an enlarged section on line 4—4 of Fig. 1. Fig. 5 represents a transverse section representing the portions of the inner sole and its attachments shown in Fig. 4 in their ultimate relation to the upper, welt, and inner sole of a welted boot or shoe.

30 The same letters of reference indicate the same parts in all the figures.

My invention is embodied in a welted boot or shoe having as a structural part thereof a laminated inner sole of which the layer 12 is or may be of the usual form and construction of an inner sole of a welted shoe and provided with the usual lip 13 turned outwardly from the outer face of the sole, and the usual channel 14 formed in the face of the sole for the reception of the inseam stitches.

In carrying out my invention I laterally extend and raise the inner edge of the layer 12, that is the edge at the inner side of the wearer's foot at the shank portion thereof, to form an instep support 15 projecting outwardly and upwardly from the usual line of this portion of the inner sole, the said instep support being formed as a structural part of the layer 12 and shoe and bearing against the inner side of the upper as shown in Fig. 5.

The preferred construction whereby the instep support 15 is formed is as follows. Upon the upper surface of the layer 12 is superimposed a pad layer 16 preferably of

flexible material such as sole leather, the layer 16 extending from the heel portion of the layer 12 forwardly and terminating at a suitable point between the shank and toe portions, its forward end being preferably under the ball of the foot as indicated in Fig. 3. Between the pad and the body of the layer 12 is interposed a stiffener layer 17 which is preferably a strip or piece of somewhat resilient although relatively stiff sheet metal such as steel. The end portions of the stiffener 17 may be secured by tacks 18 or otherwise, to the pad layer 16 and the pad and stiffener layers are preferably secured to the layer 12 by means of cement. One edge of the stiffener layer is preferably extended to or slightly outside of the inner edge of the shank portion of the layer 12 as shown in Figs. 4 and 5 and by dotted lines in Fig. 1. The extended portion of the stiffener layer is preferably given a slightly upward curve as indicated in Figs. 4 and 5. The pad layer 16 is extended outwardly from the laterally extended portion of the stiffener layer and projects upwardly as well as outwardly from the shank portion of the inner edge of the layer 12. The upward projection or inclination of the laterally extended portion of the pad layer is due in part to the upward curve of the laterally extended portion of the stiffener layer and in part to the formation of the pad layer, the section of the latter being preferably as shown in Fig. 4, that is to say the pad layer is preferably made of gradually increasing thickness from the left hand edge shown in Fig. 4 to the laterally extended portion of the stiffener layer so that its upper surface rises gradually from one edge to the opposite edge, that is from the outer to the inner edge of the sole. The outer edge of the laterally extended portion of the pad layer is beveled and meets the upper surface of the pad layer at an acute angle. The instep protector 15 thus formed is practically rigid at its base portion, while its upper edge is somewhat flexible owing to the flexibility of the material of which the pad layer is composed.

29 represents another layer consisting of a casing piece which may be of any suitable thin flexible leather, such as kid or goat skin, this being applied to the upper surface of the pad layer 16 and bent over the edges of the pad layer and layer 12 and conformed to the outer surface of the side portions of the lip 13.

The casing piece or layer 29 may be secured to the surfaces on which it bears by cement. The edge portions of the casing piece 29 constitute outer layers of the lip 13 so that the 5 operation of stitching the upper 19 and welt 20 to the layer 12 causes the inseam stitches 21 to pass through the lip portions of the casing piece as indicated in Fig. 5.

It will be seen that by the described construction a laminated instep protector is incorporated into a boot or shoe as a structural part thereof so that the supporter cannot become loosened or displaced within the shoe.

15 I claim:—

1. A welted shoe having a laminated sole portion as a structural part thereof, said sole portion comprising an inner-sole layer and a flexible instep-supporting pad layer attached 20 thereto, and a stiffener interposed between said layers.

2. A welted shoe having a laminated sole portion comprising an inner-sole layer and an instep-supporting pad layer superimposed thereon, and a flexible casing piece 25 covering the top of the pad layer and extended over the edges of the inner-sole layer and upon the channel lip.

3. An inner sole having a lip for attachment to the upper and welt of a welted shoe, 30 an instep-supporting extension at the inner edge of the shank portion, and a casing piece covering said extension, and having edge portions which are adapted to the lip of the inner sole.

In testimony whereof I have affixed my signature, in presence of two witnesses.

THOMAS J. REGAN.
